UNITED STATES PATENT OFFICE.

FRANK M. MULRONEY, OF FORT DODGE, IOWA.

BOW TIE.

Application filed March 25, 1926. Serial No. 97,345.

This invention relates to bow ties and particularly to ties designed for negligee wear, though my invention is not limited thereto, but is applicable to all forms of bow ties.

5 One of the principal objects of my invention is to provide a bow tie which will do away with the difficulty of tying a bow knot in a tie of the bat wing type, and at the same time get away from the artificial appearance of the already tied, hook on, elastic band bow.

Another object of this invention is to provide a bow tie of the character stated which may be very easily tied, in which the 15 bow portion may be made up by folding the several plies of fabric upon each other or by stitching them together but in which no actual knot is formed but only a similitude of a knot.

20 A further object is to provide a bow tie in which the neck-band portion is free from elastic, buckles, hooks, snaps, etc., which tend to wrinkle or soil the collar, and which may be used with equal advantage on soft 25 or starched collars, and which always stays at the top of the collar and looks exactly like a hand tied bow.

Other objects will appear in the course of the following description.

30 My invention is illustrated in the accompanying drawings wherein:—

Figure 1 is a perspective view of a tie constructed in accordance with my invention;

Fig. 2 is a perspective view showing the 35 manner in which the tie illustrated in Figure 1 is tied;

Fig. 3 is a perspective view of another form of my improved tie;

Fig. 4 is a perspective view of still another 40 form of tie;

Fig. 5 is a fragmentary perspective view showing a modified form of tie;

Fig. 6 is a fragmentary perspective view 45 of a tie slightly modified from that in Figure 4;

Fig. 7 is a view showing the tie in use.

In Figure 1 I have illustrated one form 50 of my improved bow tie and it will be seen from this figure that this tie consists of a relatively broad portion 10 and a relatively

narrow portion 11. The portion 10 is adapted to be folded on the lines $a-a$ and thus form a similitude of a bow, as shown in Figure 2. The extremity of the neck-band portion 11 is provided with a safety

pin 12 or any other clip of equivalent character by which this end may be attached to an undershirt or to any other portion of the clothing. In tying this bow, the neck-band portion is placed around the neck and then 60 a knot is made at the junction of the portion 11 with the portion 10. The portion 10 is folded upon the lines $a-a$ as before stated, so as to form three plies and the extended end of the portion 11 is brought up over 65 the face of the outermost of the three plies and then brought downward behind the "bow" so formed between the neck and the shirt band and brought down inside of the shirt and engaged by the safety pin with the 70 undershirt or any other garment. If this band 11 be brought down snugly over the "bow" the tie will have a complete likeness to the ordinary bow tie. It is obvious that if the portion 10 be made shorter only a 75 single or double fold, as the case might be, would be presented in the finished tie.

In Figure 3 I show another form of my invention wherein the tie itself consists of the portions 10 and 11 as previously de-

scribed, with the pin 12. The only differ-

ence between the structure shown in Fig-

ure 3 and that shown in Figure 1 is that in Figure 3 there is shown a band or loop 13

disposed diagonally to the longitudinal axis 85

of the tie and stitched at its extremities to the tie. In this instance the loop 13 serves

a double purpose. First, in case a knot is tied the loop 13 locates this knot in the

exact position necessary for a good result, 90

in relation to the portions 10 and 11. Sec-

ond, by passing the extremity of 11 down

through the loop 13 the necessity of tying

a knot is eliminated. The operation of

forming a bow is precisely the same as here-

tofore described. The portion 10 is folded

upon the lines $a-a$ so as to form a plurality

of plies. The band 11 is placed around the

neck and then inserted through the loop 13

and then brought up over the front face of 100

the bow and then it is brought downward.

The end is then tucked in behind the neck-

band of the shirt and brought down inside

of the shirt and attached to some undergar-

105

ment. In Figure 4 I show another form of tie which presents additional advantages. In this construction the bow portion 10^a at its middle is contracted in width, as at 14, by stitching or otherwise and this bow portion 110

10^a is folded upon the lines *a*—*a* heretofore described. The neck-band 11^a is not attached to the extremity of the bow portion but is attached to the bow portion 10^a inward of one end thereof as at 15, and preferably at a slight angle. Also attached to the inside face of the bow portion is a loop or band 16 which is the equivalent of the loop or band 13. Of course, the part 11^a has attached to its lower end a clip or safety pin 12 as heretofore stated. In forming this tie the bow portion 10^a is folded upon the lines *a*—*a* and the band 11^a is passed around the neck. The extremity of the neck-band is then passed downward through the loop 16, upward over the face of the bow, and then down between the neck and shirt-band into the shirt as hereinbefore described. The contracted middle portion 14 of the bow permits the two outside plies of material to be drawn inward by tightening upon the band so that the bow has a "butterfly" aspect. A tie such as last described has the advantage that it has more the appearance of a regularly tied bow than the bows heretofore described.

Preferably through not necessarily, the neck-band 11^a will be formed with a folded portion 17 for a purpose to be later stated.

30 In Figure 5 I have illustrated another form in which the three plies of material formed by folding the bow portion 10^b upon itself are stitched together by stitching 18 so that there is no necessity of forming the bow portion itself by hand but the bow portion is pre-formed and the back of this bow portion 10^b is provided with the loop 16^a as previously described, and in applying the bow the neck-band 11^b is placed around the neck, inserted through the loop 16^a carried downward and under the bow 10^b and then up over the face of the bow and then downward behind the bow and tucked down inside the shirt and engaged by a safety pin with an undergarment.

50 In Figure 6 I have illustrated still another form which is precisely the same as the form shown in Figure 4 except that in place of the single loop 16^a there are crossed loops 16^b. This tie is tied in precisely the same manner as the tie shown in Figure 4 but the crossed loops permit the tie to be turned upside down. This is for the reason that ties of this character if continuously worn with one edge up are very liable to droop but by providing two crossed loops 16^b the tie may be worn with either edge up and thus this tendency to droop is avoided. The extremity of any one of the neck-bands illustrated 55 may be provided with stiffening so that it may be more readily passed through the loop 16 or 16^b. Also any one of these bands may be formed with the portion 17. This may be let out to lengthen the band because when 60 worn constantly on the same neck that part

of the band which goes around the bow is liable to become frayed and worn. In this case when this folded portion 17 is let out the frayed and worn portion of the neck-band will be concealed within the collar.

70 One of the particular objects of this invention is that the tie in all its various forms has the same outstanding characteristic, viz, that no size element is necessary to be taken care of. In ties which are already tied or semi-tied, provision for the varying neck sizes is made in one of two ways, either by selling the tie in collar sizes or by incorporating a sliding buckle in the band portion. With a tie constructed in accordance with 80 my invention the superfluous length of the neck-band passes down between the neck and the shirt-band and is concealed beneath the shirt. It is obvious that the extremity of the neck-band portion 11, will hang down 85 further on a small neck than it will on a larger neck similar to a four-in-hand tie, except that it lies underneath the shirt, so that the matter of neck size of the wearer is taken care of automatically without the necessity 90 of any complications whatever.

95 The snubbing action of the free end passing over the bow will hold the bow in position in a manner which is particularly effective. Where a very tight collar is worn it is not even necessary to fasten the free end of the neck-band portion but it may simply hang beneath the shirt. While I have illustrated a safety pin for attaching the extremity of the band to the undershirt, union 100 suit, inner front shirt facing, or other garment, I do not wish to be limited to this as other means might be used for this purpose, for instance, a necktie clasp.

105 The method of tying which is possible with a cravat constructed in accordance with my invention makes it possible for bow ties to be sold and used with the same disregard of neck sizes as is possible with four-in-hand ties, and in selling these ties the neck 110 sizes need not be taken into consideration as the free end of my improved tie or cravat hangs down in front (but concealed beneath the shirt) a good deal after the fashion of a four-in-hand tie, and it is obvious that in 115 order to fit all average necks it is only necessary to have the free end of the cravat long enough to fit the largest average neck, say 17 inches, plus enough to wrap around the bow and an end long enough to extend beneath the shirt. The end which extends beneath the shirt should not be too short, but long enough to enable a wearer to conveniently attach same to the undergarment.

120 The object of fitting all necks with any bow tie is obvious. Thus, the dealer never loses a sale by reason of not having the right length of bow tie of the proper pattern and having the free end of the tie of ample length to fit all neck sizes is of great 125 130

importance from the point of view of the dealer and effects a big saving to him.

I claim:—

1. A tie having a relatively broad bow portion adapted to be folded upon itself to provide a plurality of plies, and a relatively long narrow neck-embracing portion extending from one end of the bow portion and adapted to be disposed around the neck of the wearer, the inner face of the bow portion having a loop permanently attached thereto and at an angle to the length of the bow portion and through which the neck-band may be engaged whereby the neck-band may be brought up under the edge of the bow portion and over the outer face thereof and then extended downward on the inside of the shirt.

2. A tie having a relatively broad bow portion adapted to be folded upon itself to provide a plurality of plies, and a relatively long narrow neck-embracing portion extending from one end of the bow portion and adapted to be disposed around the neck of the wearer, the inner face of the bow portion being formed with crossed loops through either of which the band may be disposed and brought up under the edge of the bow portion and over the outer face thereof and then tucked between the collar-band and the neck of the wearer, the crossed loops permitting the bow portion to be inverted.

3. A tie having a relatively broad bow portion formed to be folded so as to provide three plies, the middle ply being constricted at its middle, the tie having a long narrow neck-embracing portion extending from the bow portion adjacent one end thereof, there being a loop attached to the inner face of the bow portion adjacent the point of attachment of the neck embracing portion, the

neck-embracing portion being adapted to be disposed around the neck of the wearer, extend down through said loop on the inner 45 face of the folded bow portion and then upward over the outer face thereof, and having means at its extremity whereby it may be engaged with the clothing.

4. A tie having a relatively broad bow 50 portion formed to be folded so as to provide three plies, the middle ply being constricted at its middle, the tie having a long narrow neck-embracing portion extending from the bow portion adjacent one end thereof, 55 there being crossed loops disposed adjacent the point of attachment of the neck-embracing portion and the bow portion, the neck-embracing portion being adapted to be disposed around the neck of the wearer, extend 60 down through one of said loops and upward over the lower edge of the bow portion and downward on the inside of the neck-band of the shirt and having means at its extremity whereby it may be engaged with an 65 undergarment.

5. A tie having a relatively broad bow portion adapted to be folded upon itself to provide a plurality of plies, and a relatively long narrow neck-embracing portion ex- 70 tends from one end of the bow portion and adapted to be disposed around the neck of the wearer, the inner face of the bow portion adjacent its point of connection to the neck band having a loop disposed at an angle to 75 the length of the bow portion permanently attached thereto and through which the neck-band may be brought up under the lower edge of the bow portion and upward over the outer face thereof, then extended 80 downward upon the inside of the shirt and engaged with an undergarment.

In testimony whereof I affix my signature.

FRANK M. MULRONEY.
